United States Patent Office

Des. 232,331

Patented Aug. 13, 1974

232,331

SEAT

Thomas Winrow, 530 S. Sleigh St.,
Naperville, Ill. 60540

Filed Aug. 2, 1972, Ser. No. 277,432

Term of patent 14 years

Int. Cl. D6—01

U.S. Cl. D6—62

FIG. 2

FIG. 1 is a front perspective view of a furniture seat showing my design.

FIG. 2 is a modified form of the seat of FIG. 1.

The end of the sofa, not shown, is a mirror image of the side shown while the backs of both embodiments are conventional.

I claim:

The ornamental design for a seat, as shown and described.
